FLASHLIGHT

Anthony J. Desimone, Lyndhurst, N. J., assignor
to Bright Star Battery Company, Clifton, N. J.,
a corporation of New York

Application June 30, 1938, Serial No. 216,636

2 Claims. (Cl. 240—10.6)

This invention relates to flashlights.

An object of the invention is a light weight and inexpensive flashlight of attractive appearance and simple construction.

5 A flashlight embodying this invention is composed of a tubular casing, preferably flared at the bulb end and being provided at the other end with a closure having a portion threaded into the casing, both the casing and closure being composed of thermoplastic material such, for example, as the form of cellulose acetate known to the trade as Lumarith. The outer surface of the casing preferably is of polygonal contour and the casing preferably diverges slightly from the base of the flared end to the remaining end, thus providing a comfortable grip and attractive appearance. The casing may be of any desired color, but when made up in white or other light colored material will have an attractive and unusual appearance, particularly when the bulb is lighted. The thickness of the casing wall is such that in light colors it is quite translucent and a luminous condition exists along a substantial margin of the flared end at such times as the bulb filament is incandescent.

20 Other objects, novel features and advantages of this invention will become apparent from the following specification and accompanying drawing, wherein:

30 Fig. 1 is a side elevation of a flashlight embodying the invention;

Fig. 2 is a section on the line 2—2 of Fig. 1;

Fig. 3 is a plan view of the end closure;

35 Fig. 4 is a similar view of a modified form of end closure;

Fig. 5 is a section on the line 5—5 of Fig. 4, and

Fig. 6 is a fragmentary view generally similar to Fig. 2 of a modification.

40 The tubular casing 10 is provided at one end with an integral flared head 11, and at the other end with a closure 12 having a portion threaded into the casing. From a point 13 at the base of the head 11, the casing 10 diverges outwardly very slightly in the direction of the closure 12. The casing and closure 12 are composed of thermo-plastic material such, for example, as cellulose acetate and are formed by the known injection molding process. The flared head 11 is provided with a threaded recess 14 and a lens 15 of transparent cellulose acetate or other similar thermo-plastic material has an integral portion 16 threaded into the recess 14. A reflector 17 has its rim resting on the bottom of the socket

14 and engaged by the threaded portion 16 of the lens 15. The reflector 17 has a central aperture and is provided with a boss 18 in alignment with such aperture, the boss bearing of larger interior diameter than the aperture. A recessed plug 19 of insulating material is threaded into the boss 18 and a resilient contact 20 is supported in the plug by an eyelet 21, a portion of which extends outside the plug. In the aperture of the reflector 17 is arranged a standard pre-focused incandescent bulb 22 having its flange terminal 23 engaging the bottom of the boss 18 and having its center terminal 24 engaging the resilient contact 20.

10 A metallic strip 25 has an offset portion 26 projecting into a slot in the casing 10 and being attached to a button 27 as shown. Movement of the button 27 longitudinally of the casing effects longitudinal movement of the strip 20 15 25 to bring its forward end into and out of engagement with the reflector 17. The button 27 is composed of the same material as the casing 10.

The closure 12 is hollow except for a cylindrical central portion 12a in which is provided a cylindrical recess countersunk at its inner end. In the closure is received a metal cup 28 which extends somewhat beyond the end of the closure and is flared outwardly to contact the inner wall 30 of the casing 10. The strip 25 has an offset portion in continuous engagement with the cup 28 irrespective of the position of the strip. Also, in the cup is provided a spiral spring 29, one end of which rests on the bottom of the cup and the other end of which is engaged by a battery 30 in the casing 10. The terminal at the other end of the battery engages the eyelet 21 in the plug 19.

35 A spare bulb 31 is contained in the closure 12 with its flange 32 received in the countersunk portion of the central recess and with its base extending through an aperture provided for that purpose in the bottom of the cup 28. The base 40 of the bulb is surrounded by the spring 29, but is not contacted by the same. Also, the arrangement is such that the closure 12 may be disengaged from the cup 28 without in any way disturbing the bulb.

45 In the modification illustrated in Figs. 4 and 5, the central portion 12b of the closure 12, instead of being cylindrical extends diametrically across the closure. In this portion is provided a recess 50 having the same outline as that of the spare bulb 55

so that the latter may be received in the recess as clearly shown in Figs. 4 and 5.

In Fig. 6 is illustrated a different form of lens and attachment means therefor. In this modification, the flared end 11 of the casing 10 is cut back slightly and the cut-back portion is provided with threads 11a. The rim of the reflector 17 rests on the end of the cut-back portion and is engaged by the lens 33 composed of transparent cellulose acetate. A ring 34 of cellulose acetate or other similar material is provided with internal threads which engage the threads 11a. A shoulder on the ring 34 engages the lens 33 to hold it in assembled relation to the casing.

15 Since the lens is composed of transparent cellulose acetate, it is non-breakable. Also, because of the inherent characteristics of cellulose acetate, the casing is very sturdy and capable of withstanding high pressures for distortion. Furthermore, in view of the almost complete absence of exposed metal, the flashlight may be used around electrical apparatus without any fear of short circuiting the electrical apparatus through the medium of the flashlight casing.

25 In the embodiment illustrated in Figs. 1 and 2, when the casing is composed of white or other light color material, light from the bulb is transmitted laterally through the translucent portion 16 and the corresponding portion of the flared end 30 of the casing to render the same luminous and give a very unusual and attractive appearance to the flashlight. Such corona effect is enhanced by the fact that the lens 15 extends beyond the edge of the flared end. Such corona effect, while 35 present in the embodiment of Fig. 6, is not so pronounced due to the fact that the reflector extends more nearly to the end of the casing.

I claim:

1. A flashlight comprising a tubular casing of

insulating material having a threaded recess at one end, a metallic reflector having its rim engaging the bottom of said recess, said reflector having a rearwardly extending interiorly threaded hollow hub formed with an inwardly projecting shoulder for engagement by the flange of a pre-focussed bulb, an exteriorly threaded hollow plug of insulating material arranged in the end of said hub to receive the base of said bulb, a spring contact in said plug for engagement by the center contact of said bulb, a lens having an integral threaded portion fitting into said threaded recess and engaging said reflector ring, and a conductor slidably supported by said casing in contact with the inner wall thereof for movement into and out of contact with said reflector.

2. A flashlight comprising a tubular casing of insulating material having a threaded recess at one end, a metallic reflector having its rim engaging the bottom of said recess, said reflector 20 having a rearwardly extending interiorly threaded hollow hub formed with an inwardly projecting shoulder for engagement by the flange of a pre-focussed bulb, an exteriorly threaded hollow plug of insulating material arranged in the end of said 25 hub to receive the base of said bulb, a spring contact in said plug for engagement by the center contact of said bulb, a lens having an integral threaded portion fitting into said threaded recess and engaging said reflector rim, a conductor slidably supported by said casing in contact with the inner wall thereof for movement into and out of contact with said reflector, a recessed closure of insulating material having a portion threaded into another end of said casing and a metal cup in 30 said closure having its rim engaged by said conductor.

ANTHONY J. DESIMONE.
